Attorney,

UNITED STATES PATENT OFFICE.

FRANK BOWEN, OF MONETT, MISSOURI.

FIGURE TOY.

Application filed August 20, 1921. Serial No. 493,835.

To all whom it may concern:

Be it known that I, FRANK BOWEN, a citizen of the United States, residing at Monett, in the county of Barry and State of Missouri, have invented a new and useful Figure Toy, of which the following is a specification.

This invention relates to toys, and more particularly to figured toys, the primary object of the invention being to provide novel means for reciprocating the figures in vertical planes to simulate persons peeping over a wall.

A further object of the invention is to provide a container for the figures, the container being divided into compartments to accommodate the supporting means and their figures, novel means being provided and extending through the base of the container for imparting reciprocatory movement to the figures.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 is a vertical sectional view through a container disclosing the figured members as supported therein.

Figure 2 is a side elevational view of the same, and

Figure 3 is a sectional view taken on line 40 3—3 of Figure 1.

Referring to the drawing in detail, the device includes a container indicated generally by the reference character 5 which container includes a rear wall 6, side walls 45 7, front wall 8 and bottom wall 9.

The rear wall 6 is of a length greater than the front and side walls of the container, the same being shown as extending above the upper ends of the side and end walls to provide a gripping means to permit the device to be securely held by a person operating the same.

A partitioning wall divides the container into lateral compartments 11 and 12 respec-

tively in which the respective figures to be 55 hereinafter more fully described, move. Supported in suitable openings in the front and rear walls of the container, is a shaft 13 which is provided with crank arms 14 and an operating handle 15, the crank arms 60 being oppositely disposed so that the heads of the figures supported thereby will move at intervals to positions above the upper edges of the partitioning member 10.

Mounted on each crank arm 14 are the 65 bases 16, which bases provide supports for the figures 17 which in the present showing, are constructed to simulate children, suitable means being provided at the upper end of each base 17 for embracing the feet of the 70 figure associated therewith for securing the figure to the base.

The securing means is indicated at 18 and is in the form of a flexible wire which may be bent around the upper end of the base to 75 which the same is secured, there being provided a groove 19 adjacent to the upper end of each base to accommodate the wire securing means.

In the operation of the device, a person 80 by rotating the operating handle 15, causes the bases 16 and the figures supported thereon to be moved alternately through their compartments, the heads of the figures extending above the upper edge of the container to simulate children peeping over a wall.

Having thus described the invention, what is claimed as new is:—

A toy including a container, a partitioning member in the container dividing the same into compartments, crank arms supported at the base of the compartments, base members having connection with the crank arms and having grooves formed adjacent 95 to their upper ends, figured members supported on the bases, and flexible securing means embracing portions of the figured members and lying in the grooves to prevent displacement thereof.

In testimony that I claim the foregoing as my own, I have hereto affixed by signature in the presence of two witnesses.

FRANK BOWEN.
